(57) **CLAIM**

The ornamental design for a liquid and lotion applicator, as shown and described.

DESCRIPTION

FIG. 1 is a top perspective view of a liquid and lotion applicator showing my new design;

FIG. 2 is a bottom perspective view thereof;

FIG. 3 is a side view, the opposite side is a mirror image thereof, except for the screw threading on the neck;

FIG. 4 is a bottom plan view thereof;

FIG. 5 is a perspective view of a second embodiment of the liquid and lotion applicator;

FIG. 6 is a top plan view of the second embodiment, the bottom plan view is the same except for the screw threading on the neck; and,

FIG. 7 is a side view, the opposite side is the same except for the screw threading on the neck.
